UNITED STATES PATENT OFFICE.

FREDERICK A. DILLINGHAM, OF TROY, OHIO, ASSIGNOR TO THE TROY CARRIAGE SUNSHADE COMPANY, OF TROY, OHIO, A CORPORATION OF OHIO.

WEATHER-CAP FOR SWINGING SASHES.

1,243,285.

Specification of Letters Patent.

Patented Nov. 27, 1917.

Application filed May 14, 1917. Serial No. 168,503.

To all whom it may concern:

Be it known that I, FREDERICK A. DILLINGHAM, a citizen of the United States, residing at Troy, in the county of Miami and 5 State of Ohio, have invented certain new and useful Improvements in Weather-Caps for Swinging Sashes, of which the following is a specification.

My invention relates to automobile wind 10 shields and more particularly to a form of water cap or sash frame heading so constructed and arranged as to overlap the opposing sash member to form a weather strip or sealing strip to exclude air and moisture.

15 The object of the invention is to improve the structure as well as the means and mode of operation of such devices whereby they will not only be cheapened in construction but will be more efficient in use, positive in 20 operation, secure in their adjustments, and unlikely to get out of repair.

It has been customary heretofore to provide a weather strip or heading of rubber or other flexible material which is fitted to 25 the edge of the glass of one sash section in such relation as to overlap the edge of the glass of the other section when the sashes are alined. As now commonly employed this weather strip extends only upon the 30 glass of the wind shield from one inner side of the sash frame to the other. It is customary to provide the exposed ends of the sash frame with a metallic water cap shaped to conform to the sash frame and overhanging 35 the edge of the glass a limited distance at points in proximity to the frame. Inasmuch as the weather strip or sealing strip now commonly employed extends only from one water cap or head cap to the other, there 40 is left a short space at each end of the glass supported weather strip which is unprotected and through which the air may freely circulate. This unprotected space comprises a crevice intermediate the water or 45 head caps of the opposing sash members.

To provide means for effectively closing or sealing this terminal space at each end of the weather or sealing strip now commonly employed, and intermediate the water or head caps which inclose the ends of the sash frames is one of the primary objects of the present invention.

A further object of the invention is not only to provide means for effectively closing 55 this opening, but to provide improved means

for attaching such closure or overlapping weather strip whereby they will not be readily disengaged or displaced by violent contact of the opposing sash member.

With the above primary and other incidental objects in view as will more fully appear in the specification, the invention consists of the features of construction, the parts and combinations thereof, and the mode of operation or their equivalents, as herein after described and set forth in the claims.

Referring to the drawings Figure 1 is a perspective view of adjacent portions of two opposing wind shield sections or other sashes to which the overlapping cap of the sash frame, forming the subject matter hereof has been applied. Fig. 2 is a perspective view of a portion of the sash member carrying the protective cap forming the subject matter hereof, viewed from the inside. Fig. 3 is an inverted perspective view of the cap removed from the sash. Fig. 4 is a bottom plan view thereof. Fig. 5 is a transverse sectional view thereof.

80 Like parts are indicated by similar characters of reference throughout the several views.

Referring to the drawings, 1 represents one of the sash members, while 2 indicates the opposing member, such members being in their closed position, or in a common plane. Mounted upon the edge of the glass of one sash member, preferably the lower member of the pair, is a weather strip 3, of rubber or other similar material having a vertically disposed flange 4 which overlaps the glass of the second or opposing sash member. Secured to the exposed end of the opposing or upper sash frame member 5 is a water cap or head cap 6, of metal, which at the inner side of the sash frame 5 is contracted as at 7 to conform to the thickness of the sash glass which it overhangs a short distance. At the present time it is customary to provide the lower sash 1 with a similar water cap or head cap, placed and arranged similar to the cap 6, secured to and inclosing the exposed end of the lower sash frame member 8 and abutting at its inner end against the end of the glass supported weather or sealing strip 3. Inasmuch as clearance space is necessary intermediate the water or head caps of the respective sash members, in order to permit the relative 105 110

swinging movement of the sashes an unprotected opening or crevice results.

To overcome this difficulty and to provide continuous and complete protection for the wind shield or sash joint from one extreme of the sash frame to the other, there is provided a water or head cap 9 supported upon and inclosing the upper end of the lower sash frame member 8 of a shape and proportion quite similar to the opposing water or head cap 6 except that the cap 9 is provided with marginal fingers or tines 10. This cap 9, and likewise the cap 6 is secured to the sash frame by means of a screw 11, extending through the table of the cap and engaging a screw threaded hole in a block or insert 11', positioned within the interior of the sash frame member if the latter is formed of sheet metal, as shown in Fig. 5 or in sash frame member itself in the event that the latter is solid.

The head or cap 9 is contracted at its inner end as at 12 in a manner corresponding to the contraction 7 of the cap 6.

Mounted upon the head or water cap 9 and inclosing the same is a protective covering or supplemental cap 14 preferably of rubber or some similar material but which may, if so desired be of rigid or non-yielding material. The covering or protective cap 14 is shaped to conform to the general contour of the primary cap or head 9 which it incloses and is contracted at its inner end to agree in cross sectional shape with that of the glass supported weather strip 3. The protective covering or supplemental cap 14 is provided adjacent to its outer edge with an upturned integral flange or lip 15 shaped to conform to the contour of the cap 6 of the opposing sash section. The flange 15 terminates at the inner end of the cap 14 in a position flush with the flange or lip 4 of the glass supported weather strip 3. The flange or lip 15 of the cover or supplemental cap 14 forms a continuation of the flange 4 of the glass supported weather strip and over-laps the cap 6 of the upper or opposing sash section thereby closing the intervening clearance space or crevice.

If means was not provided for securing the protective covering or cap 14 in position upon the primary cap 9 the violent impingement of the opposing sash 6 upon the flange 15 would tend to unseat or disengage the protective covering or auxiliary cap 14 from the primary cap 9. To obviate such possibility and insure the retention of the auxiliary covering or supplemental cap 14 in its adjusted position, the side portions of the cap 14 are extended downward beyond the limit of the side walls of the primary cap 9, and at their lower edges are flanged or shouldered inward as indicated at 16. Such flange or shoulder engages over the edge of the side wall of the primary cap

serving to clench the parts in engagement one with the other. To further secure the parts in engagement, the fingers or tines 10 formed integral with the primary cap or head 9 are bent outward and upward over the sides of the protective covering or auxiliary cap 14 thereby preventing the accidental disengagement of the flanged or shouldered edges 16 of said supplemental cap from the edge of the side walls of the primary cap 9.

It will be obvious that if a rigid flange or lip is desired or is suitable to the conditions of use such rigid lip or flange may be formed integral with the primary cap 9 and the auxiliary covering supplemental cap 14 of flexible material may be omitted. In such event the rigid flange or lip would form a permanent stop for the opposing sash section. In either form of embodiment the lip or flange carried by the cap or head is preferably positioned to form a continuation of the flange member 4 formed upon the glass supported weather strip 3 to effectively close the clearance space between the opposing sash frame members and provides a continuous protection from one extreme side of the sash or wind shield frame to the other.

If so desired the auxiliary head 14 and the glass supported weather strip 3 may be formed integral one with the other. In such case of course a cap 14 will be formed at each end of the weather strip 3. Inasmuch as wind shields are not always constructed of the same width, it will be found more economical however to form the supplemental or protective cap 14 independent of the weather strip 3 against which the inner end of the cap is firmly abutted.

From the above description it will be apparent that there is thus provided a device of the character described, possessing the particular features of advantage before enumerated as desirable but which obviously is susceptible of modification in its form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

Having thus described my invention, what I claim is:—

1. The combination with two relatively movable sash members, of a cap fitted upon

the end of the frame member of one sash and a projecting flange upon said cap adapted to overlap the frame member of the opposing sash.

5. 2. The combination with two relatively movable sash members and a weather strip carried intermediate the side frames of one sash and overlapping the other sash member of a cap carried upon each side member of 10 the sash frame of one sash, and a flange projecting from said cap registering with and forming a continuation of said overlapping weather strip.

3. The combination with a swinging sash, 15 of a primary or base cap fitted upon the sash frame, and a supplemental cap of yielding material fitted upon said base or primary cap, and a projecting flange or weather lap upon said supplemental cap.

20 4. The combination with a swinging sash, of a frame cap secured thereto, a flanged inclosure for said cap, and projecting tines upon said cap clasping said flanged inclosure.

25 5. The combination with a swinging sash, of a frame cap secured thereto, a flanged inclosure for said cap, and underhanging flanged edges upon said inclosure engaged beneath the edges of the cap.

30 6. The combination with two relatively movable sashes, and a weather strip carried by one of said sashes and overlapping the other sash intermediate the side frame members thereof, of flanged frame caps carried 35 by one of the sashes registering with the overlapping weather strip and overlapping the side frame members of the opposing sash.

7. The combination with two relatively 40 movable sashes, and a weather strip carried by one of said sashes and overlapping the other sash intermediate the side frame members thereof, a base cap of rigid material

carried by the sash frame, a supplemental cap of yielding material engaged with the 45 base cap, and a flange projecting from the supplemental cap overlapping the opposing sash.

8. The combination with two relatively movable sashes, and a weather strip carried 50 by one of said sashes and overlapping the other sash intermediate the side frame members thereof, a base cap of rigid material carried by the sash frame, a supplemental cap of yielding material engaged with the 55 base cap, fingers or tines projecting outwardly and upwardly from the base cap and inclosing the supplemental cap, and a flange carried by the supplemental cap overlapping the opposing sash. 60

9. The combination with two relatively movable sashes, and a weather strip carried by one of said sashes and overlapping the other sash intermediate the side frame members thereof, a base cap of rigid material 65 carried by the sash frame, a supplemental cap of yielding material engaged with the base cap, interlocking shoulders upon the base and supplemental caps, and a flange carried by the supplemental cap overlapping 70 the opposing sash.

10. The combination with two relatively movable sashes, and a weather strip carried 75 by one of said sashes and overlapping the other sash intermediate the side frame members thereof, and a laterally distorted continuation of said weather strip at each end of the portion intermediate the side frame members adapted to overlap the side frame members of the opposing sash. 80

In testimony whereof, I have hereunto set my hand this 5th day of May, A. D. 1917.

FREDERICK A. DILLINGHAM.
